UNITED STATES PATENT OFFICE

JOSEPH KWIATKOWSKI, OF PERTH AMBOY, NEW JERSEY

WORK-HANDLING CRANE FOR LOCOMOTIVE APPURTENANCES

Application filed July 5, 1928. Serial No. 290,572.

This invention relates to certain new and useful improvements in work handling crane for locomotive appurtenances and has for its primary object to provide a hoisting mechanism and crane structure adapted for handling locomotive appurtenances, and more particularly the pump structures thereof in removing the pump structure from the side of the locomotive for repair work or the like and for the replacement thereof.

A further object of the invention is to provide a work handling crane of the above type capable of being manually set in position adjacent a track structure and engageable with a part of a locomotive to provide a support for a forward projecting end thereof during removal and replacement of a pump structure.

With the above and other objects in view that will become apparent as the nature of the invention is better understood, the same consists in the novel form, combination and arrangement of parts hereinafter more fully described, shown in the accompanying drawings and claimed.

In the drawings:—

Figure 1 is a side elevational view of the work handling crane for locomotive appurtenances illustrated as associated with a locomotive and side pump structure illustrated in front elevation;

Figure 2 is a top plan view of the crane structure showing the forwardly positioned vertically adjustable supporting arm engaged with a side pipe section on the locomotive body;

Figure 3 is a front elevational view of the crane; and

Figure 4 is an enlarged fragmentary detail sectional view showing the adjustable mounting for the forwardly positioned vertically adjustable crane supporting bar.

The crane structure disclosed herein is intended for association with a steam locomotive, particularly for handling the pump device located at one side of the locomotive in removing the same for repair work or the like and for replacement thereof, the locomotive being designated by the reference character L while the pump device carried by the locomotive is denoted by the reference char-

acter P. The crane structure comprises a frame that may be manually moved into position relative to the locomotive with a traversing hoist or block and tackle mechanism carried thereby for handling the pump P during removal and replacement thereof.

The crane structure is in the form of a triangular frame having a pair of forward upwardly converging legs 5 and a single vertical rear leg 6, the forward legs 5 being connected together adjacent their lower ends by the cross brace 7, while longitudinal and horizontal brace rods 8 extend between the single rear leg 6 and the two forward legs 5. The lower ends of the legs taper as at 8 to obtain a more secure purchase in the ground G. This idea is clearly illustrated in Figures 1 and 3. The upper ends of the forward legs 5 are connected by a cross head 9.

The crane structure further includes a track rail 10 in the form of an I-beam that is mounted at the upper ends of the legs 5 and 6 with the forward end 10a thereof projecting beyond the forward legs 5. The travelling hoist comprises a carriage 11 having four corner bearings 12 with a roller bearing wheel 13 carried by each corner and riding upon the adjacent base flange 14 on the I-beam or track rail 10. Block and tackle devices 15 depend from the carriage 11 and are adapted to be engaged with the pump P as illustrated in Figure 1.

When the crane structure is in the position shown in Figure 1, the forward projecting end 10a of the track rail 10 is disposed above the side running board of the locomotive L and carries a vertically adjustable bar at its outer end for engagement with the pipe line or hand rail R as shown in Figures 1 and 2. A tubular guide 16 is suitably secured to the forward end of the rail extension 10a and the bar 17 is vertically adjustable therein, the bar being provided with a plurality of vertically spaced transverse openings 18 that are adapted to be moved into registration with openings 19 formed in the tubular guide and through which aligned openings the pin 20 is extended as illustrated in Figure 4 for holding the bar 17 in adjusted position. The pin 20 is carried by a cord or chain 21 that

is attached to the rail or guide. The lower end of the bar 17 carries a head 22 having a groove 23 formed in its lower end to receive a pipe line or hand rail R and be engaged therewith as shown in Figure 1. When the crane structure is associated with the locomotive as illustrated in Figure 1, the forward projecting end 10a of the track rail 10 is supported at its extreme forward end upon a convenient part of the locomotive. Lifting handles 24 are carried by the legs 5 and 6 and are employed for placing the crane structure in position.

The pump P is removed by the block and tackle devices 15 and carriage block 11 as indicated by dotted lines in Figure 1 and as the pumps are quite heavy and the crane structure is of a portable nature, it is possible to handle and shift the pumps in a fast and efficient manner. When the carriage block 11 is in the full line position shown in Figure 1 with the pump P suspended therefrom, the forward projecting end 10a of the track rail 10 is supported on a convenient part of the locomotive body so that overbalancing of the track rail is prevented.

While there is herein shown and described the preferred embodiment of the present invention, it is nevertheless to be understood that minor changes may be made therein without departing from the spirit and scope of the invention as claimed.

What I claim as new is:

In a hoisting apparatus for the purpose specified, comprising a supporting frame and a horizontal projecting beam adapted to sustain suitable hoisting mechanism, a vertical tubular member secured to the forward end of said beam, a vertically adjustable bar slidably mounted in said tubular member, and provided at its lower end with a grooved block to engage with a pipe line or rail on a locomotive engine and rest thereon, said tubular member and said adjustable bar being formed with holes to receive a holding pin and said beam being formed with a socket to seat said pin and hold the adjustable member in place.

In testimony whereof I affix my signature.
JOSEPH KWIATKOWSKI.
